UNITED STATES PATENT OFFICE.

ALEXANDER ALEXANDROVITCH GOLOVTCHIKOFF, OF TOKYO-fu-ka, JAPAN, ASSIGNOR
OF ONE-HALF TO SHUN ICHI ONO, OF TOKYO, JAPAN.

FIRE GRATE WITH MOVABLE HOLLOW FIRE BARS.

Application filed February 4, 1925. Serial No. 6,845.

This invention relates to a fire-grate with movable hollow fire-bars wherein each hollow fire-bar is provided with small openings in its bottom surface allowing air to enter 5 into a combustion chamber under the fire-grate. Each hollow fire-bar is further provided with a trunnion entering into an opening of the common cast iron lever which makes it possible to move said trunnion in a 10 circular sidewise movement. Fire-bars thus made are set in iron boxes at their ends so that the bottom plate of the box is at the same time a foundation for the fire-bars. These boxes are fastened in the brick work 15 and have at their back side apertures which are connected either with the outward air or with the air canals of the stove.

This invention has for its object to provide a fire-grate which is designed mainly 20 for stoves with reversed draught in order to get hot air under the fire-grate for the purpose of reburning the gases which have not been burnt completely in the heating device.

A further object of the invention relates 25 to a most convenient type of the fire-grate for cleaning away the ashes and dross.

One embodiment of this invention is illustrated by way of example in the accompanying drawings in which:—

30 Fig. 1 is a sectional elevation of the fire-grate along the line 1—1 of Fig. 3.

Fig. 2 is a horizontal section of the fire-bar on the line 2—2 of Fig. 1.

Fig. 3 is a plan view of the fire-grate.

35 Fig. 4 is a lateral section of the fire-grate along the line 4—4 of Fig. 3.

Fig. 5 is the same along the line 5—5 of Fig. 3.

Fig. 6 is a front view of the fire-grate 40 from the left hand side of Fig. 3.

Fig. 7 is a cross section of the fire-grate along the line 7—7 of Fig. 3.

As shown in the figures, the fire-grate 45 consists of hollow fire-bars 1 which have small openings 2 at the bottom surfaces and are placed into two cast iron boxes 4 and 4'. For this object the bottom surface of the box is casted with half cylindrical grooves into which each cylindrical end 3 of the fire-bars 50 is resting. Every fire-bar has an angle shaped point 5 at the end and the ends of these points enter into the opening 7 of the common cast iron plate 6. The plate is rotated partially to and fro according to the 55 reciprocal motion of said plate by means of

the projecting handle 8 outside of the stove.

In order to avoid fuel falling into the boxes 4 and 4' and to make same air-tight, cast iron walls 9 and 9' are fitted slidably to inner sides of said boxes from the side 60 of the heating device.

The cast iron plate 6 passes through the brick work along pipes 10 and 10' of rectangular section which are engaged with both ends of the box 4 and the boxes 4 and 4' 65 have apertures 11 and 11' respectively at the outer sides for the influx of air which passes through the hollow bars 1 and the upper and lower edges of these boxes are fastened in the brick work. 70

When the cast iron plate 6 is moved back and forth by means of the handle 8, the fire bars 1 swing around their axis shaking the ashes down and the air which enters through the boxes, the hollow bars and their bottom openings 2, is directed under the fire-grate in the heated condition effecting the complete combustion of unburned gases 75 which are caused by reversed draught. 80

Claims:—

1. In a grate, a series of parallel cylindrical hollow fire bars having both ends open and a series of perforations in the bottom of each bar, the ends of said bars resting in cast-iron boxes having semi-cylindrical 85 grooves on the bottoms thereof to receive the ends of said fire bars, each fire bar being provided with an angular upright member placed above the end thereof, said members resting in a cast-iron plate fitted in one of said boxes and means for reciprocating said plate. 90

2. In a grate, a series of parallel hollow fire bars having both ends open and a series of perforations in the bottom of each bar, 95 the ends of said bars resting in cast-iron boxes having semi-cylindrical grooves on the bottoms thereof to receive the ends of said fire bars, each fire bar having an angular member on the end thereof, said members terminating in a cast-iron plate fitted in one of said boxes and a handle on said plate on the outside of said box to permit the simultaneous reciprocation of all of said bars. 100

3. In a grate, a series of parallel hollow fire bars having both ends open and a series of perforations in the bottom of each bar, the ends of said bars resting in cast-iron 110 boxes having semi-cylindrical grooves on

the bottoms thereof to receive the ends of said bars, said ends opening into said cast-iron boxes, one end of each fire bar being fitted with a pointed upright member resting in a cast-iron plate fitted in one of said boxes and a handle on said plate so that all of said bars may be simultaneously re-

ciprocated, said cast-iron boxes communicating with the outward air or with the combustion chamber of the fire box.

10

In testimony whereof I hereunto affix my signature.

ALEXANDER ALEXANDROVITCH GOLOVTCHIKOFF.
